(57) CLAIM

The ornamental design for a carrier for articles, as shown and described.

DESCRIPTION

FIG. 1 is a perspective view of a carrier for articles showing my new design.

FIG. 2 is a rear elevation of a carrier for articles showing my new design.

FIG. 3 is a left side elevation of a carrier for articles showing my new design.

FIG. 4 is a right side elevation of a carrier for articles showing my new design.

FIG. 5 is a top plan view of a carrier for articles showing my new design.

FIG. 6 is a front elevation of a carrier for articles showing my new design; and,

FIG. 7 is a bottom plan view of a carrier for articles showing my new design.

Any broken-line illustration appearing in the drawings is for illustrative purposes only and forms no part of the claimed design.
